UNITED STATES PATENT OFFICE.

DAVID R. BONE, OF OGLESBY, TEXAS.

FURNACE.

1,229,706.

Specification of Letters Patent. Patented June 12, 1917.

Application filed August 22, 1916. Serial No. 116,218.

To all whom it may concern:

Be it known that I, DAVID R. BONE, a citizen of the United States, residing at Oglesby, in the county of Coryell and State of Texas, have invented certain new and useful Improvements in Furnaces, of which the following is a specification.

My invention relates to a system of producing heat for kilns, furnaces for burning lime, furnaces for boilers, and similar purposes, and the object is to provide apparatus for consuming all the fuel fed to the furnaces and for pre-heating the air which is fed to the furnaces and for excluding all air which has not been preheated. The object is to feed the fuel to furnaces in such form that it can all be consumed and to furnish enough oxygen to oxidize and combine with all the carbon elements. Another object is to provide apparatus by which lignite and cheap coal can be utilized with economy and saving of expense and labor. Other objects and advantages will be fully explained in the following description and the invention will be more particularly pointed out in the claims.

Reference is had to the accompanying drawings which form a part of this application.

Figure 1 is a vertical section of the furnace and apparatus for burning the fuel and preheating the air, showing a kiln in conventional form connected to the furnace. Fig. 2 is an enlarged sectional view of a stoker. Fig. 3 is a longitudinal section of the revolving feeder.

Similar characters of reference are used to indicate the same parts throughout the several views.

The results of the system herein described are obtained by admitting only preheated air to the fire zone where combustion of fuel gases is taking place either in a furnace for supplying heat to a kiln or inside a kiln or for a furnace for supplying heat for boilers or for other purposes. In the drawings, a kiln 1 is shown in conventional form provided with a stoker 2 and a flue 3. A furnace 4 is provided with grate bars 5, a door 6, and stokers 7. Instead of placing an ash box under the grate bars 5, as usual, a chute 8 is provided with a flared upper end or mouth 9 to receive the ashes and hot embers which fall through the grate bars 5. The ashes fall down the inclined chute to a box 10 from which they can be removed

through a door 11. Provision is made for a fire within the box 10. Grate bars 12 are provided for receiving the fuel and supporting the same for combustion. The object 60 of the fire in box 10 is to heat all the air that is fed to the furnace 4. The air is heated not only by the fire which is maintained in the box 10, but is also heated by the embers which fall through the grate bars 65 5. The box 10 is provided with a door 13, which may be used in supplying fuel to fire on the grate bars 12 and for admission of air which is to be heated. The heated air will rise up through the fuel 14 which 70 is being consumed in the furnace 4. The fuel for furnace 4 is preferably fed in powdered form by means of stokers 7. The fuel will fall into the fire zone 15 where the particles of fuel will be oxidized and largely 75 converted into gas. The heat and gases will pass directly into the kiln 1. A plurality of stokers 7 may be provided and each stoker consists of a casing 16 which has openings 17 into a hopper 18 which contains fuel and 80 corresponding openings 19 for dropping the fuel into the fire zone 15 and furnace 4. The fuel is fed by means of a revolving feeder 20. The feeder 20 may be revolved by any suitable means. In operation a cavity 21 85 formed in the feeder will be turned to an opening 17 in the casing 16 and instantly a charge of fuel will fill the cavity 21 in the feeder and on continuous revolving of the feeder the charge of fuel will be dumped 90 into the furnace 4 through the opening 19 in the casing 16, and on each revolution of the feeder 20, each cavity 21 will gather a charge of fuel and dump the same into furnace 4. In order to prevent air from entering the furnace 4, short pipes 23 may be connected with casing openings 19 and project down into the furnace 4.

A valve or damper 24 is provided for regulating the flow of heated air through 100 the chute 8. A valve or damper 25 is also provided for regulating the passage of heat and burning gases from the furnace 4 into the kiln 1.

The fire on the grate bars 12 may be a 105 slow burning fire to heat the incoming air which will rise through the chute into the main furnace 4. The air in going up the chute will be further heated by the falling embers from the grate bars 5. The air will 110 thus be preheated before it comes in contact with the fuel in the furnace 4 where the

principal combustion takes place. The cold air or air in the normal atmospheric condition is thus excluded and only preheated air is let into the main furnace. The burning of the fuel will create the necessary draft to force the heat and burning gases into the kiln 1. The air is subjected to a process of preheating and after the air is thus treated, only such quantity of air as is necessary and no more than is needed is allowed to enter the furnace for oxidizing the contents of the combustion chamber, and as no forced draft is allowed, the pressure necessary to convey the heat created by the burning gases to the point where it is to be utilized is created by expansion, additional heated air being supplied as needed to effect the combustion of the gases. Various changes in the sizes and proportions, construction and arrangement of the several parts may be made without departing from my invention. The excluding of the cold air from the furnace is important because the combustion will not be impeded or hindered by the cold air. The heat produced is thus conserved, as the heat will not be consumed in heating cold air.

What I claim, is,—

1. A heat producing apparatus comprising a furnace provided with grate bars, means for feeding fuel to said furnace, a combined ash and heated air chute depending from said furnace, a fire-box at the termination of said chute, and grate bars for maintaining a fire in said fire-box.

2. A heat producing and heat conserving apparatus comprising a furnace provided with means for maintaining fuel in said furnace, a combined ash and heated air chute depending from said furnace, a fire-box at the termination of and communicating with said chute, a door for said fire-box, and provision therein for maintaining a fire.

3. A heat producing and heat conserving apparatus comprising a furnace in communication with a kiln, stokers for supplying fuel to said furnace, grate bars for supporting fuel in said furnace, and means for pre-

heating air to be fed to said furnace consisting of a combined ash and heated air chute depending from said grate bars at an incline and a fire-box at the termination of and communicating with said chute.

4. A heat producing and heat conserving apparatus comprising a furnace in communication with a kiln, grate bars for supporting fuel in said furnace, stokers for feeding fuel to said furnace, means for excluding cold air from said furnace, and means for preheating air and feeding the same to said furnace consisting of a chute depending from said grate bars for receiving ashes from said grate bars and a fire-box at the termination of and communicating with said chute, and means for maintaining a fire in said fire-box for heating air and forcing the same up said chute into said furnace.

5. A heat producing and heat conserving apparatus comprising a heat-producing furnace in communication with a kiln or curing furnace, means for supporting fuel for combustion in said furnace, stokers for feeding fuel thereto, means for excluding unheated air from said furnace, an inclined chute depending from said furnace, a valve for intercepting the passage through said chute, and a heat-producing member at the termination of and communicating with said chute.

6. A heat producing and heat conserving apparatus comprising a heat producing furnace in communication with a kiln or curing furnace, grate bars supporting fuel in said heat-producing furnace, stokers for feeding fuel thereto, a combined ash and heated air chute depending from said grate bars for removing ashes therefrom, a heat-producing member at the termination of said chute and communicating therewith for heating air and forcing the same through said chute and through embers falling from said grate bars, and means for excluding cold air from said furnace.

In testimony whereof, I set my hand, this 18th day of August, 1916.

DAVID R. BONE.
